GEORGE H. BAUGHMAN AND FRANK J. SEMRADEK, OF CHICAGO, ILLINOIS.

CLAMP FOR SALES-BOOK PADS.

1,156,876.

Specification of Letters Patent.

Patented Oct. 19, 1915.

Application filed August 29, 1914. Serial No. 859,146.

To all whom it may concern:

Be it known that we, GEORGE H. BAUGHMAN and FRANK J. SEMRADEK, both citizens of the United States, and residents of Chicago, in the county of Cook and State of Illinois, have invented certain new and useful Improvements in Clamps for Sales-Book Pads, of which the following is a full, clear, and exact specification.

Our invention relates to what are commercially known as sales-books, that is binders for suitably and conveniently holding a pad of sales checks, sales tickets or the like such as are usually employed in mercantile establishments for memoranda of purchases made by customers. The pages or tickets of these pads are adapted to be torn out by the sales person making the sale and when a pad has been entirely used the stub thereof is adapted to be replaced by another pad which is inserted between the covers of the said book after the said stub has been removed.

More particularly our invention pertains to the devices for removably clamping and holding the pad between the binding covers of the book member and its particular object is the provision of a clamp that is easy for the sales person to manipulate when removing or replacing a pad.

Another object is to construct a clamp of the type mentioned that will securely and firmly hold the pad when the latter is placed between its clamping jaws. A still further object is the provision of a clamp that is inexpensive to manufacture so that it will not materially add to the retail cost of the sales book.

These and other objects we prefer to accomplish by the means and in the manner hereinafter fully described and as more particularly pointed out in the claims, reference being had to the accompanying drawings forming a part of this specification wherein similar reference characters indicate the same parts in the various figures.

In the drawings:—Figure 1 is a perspective view, partly fragmentary, of a sales-book in opened position showing our invention applied thereto and gripping a pad of sales checks. Fig. 2 is a rear elevation of the clamping members, detached from the book and in their respective positions for clamping a pad. Fig. 3 is a view similar to Fig. 2 but showing the clamping members opened. Fig. 4 is a transverse vertical sec-

tion of the book taken on the line 4—4 of Fig. 1.

For the purpose of convenience in describing our invention we have herein illustrated and described the same embodied in a sales-book, but it of course will be obvious to others skilled in the art to which it relates that the principles involved may be readily applied without alteration or change to binders for loose-leaf ledgers, transfer-books, files and the like. We therefore desire it understood that such uses and applications are contemplated by us.

Referring to the drawings A and B represent respectively the top and bottom covers of a sales-book that are usually constructed of relatively stiff material and are hinged or connected together by means of a suitable flexible back portion C, substantially as shown in Figs. 1 and 4 of the drawings. Secured upon the inside surface of cover B and disposed in a transverse plane substantially parallel with the "back" edge thereof is the stationary clamping jaw or member 5 of the clamp. This stationary jaw 5 preferably comprises an elongated strip of angular sheet metal, substantially L-shaped in cross-section that is so arranged that one of its members is disposed at a right angle to said cover and projects upwardly therefrom, while its opposite member, which is slightly upturned or flared as at 6 along its outer edge, is preferably secured to said cover by means of rivets 7 or in any other suitable manner. The co-operating or movable clamping jaw 8 is likewise preferably constructed of angular sheet metal of a substantially L-shape as shown and is inverted or disposed so that its vertical member lies flat against, and, as will hereinafter be described, is adapted to be clamped to the vertical upstanding portion of the lower or stationary jaw. The horizontal member of jaw 8 preferably slopes or is inclined slightly downwardly toward the adjacent cover B and its outer free edge is inturned or flared as at 9. While it is not considered essential we desire to construct these clamping jaws so that one of their flared edges (preferably the upper edge) will overhang the opposing flared edge in a plane beyond the vertical plane the same as clearly illustrated in Fig. 4 of the drawings.

In order to accomplish the relative movement and clamping operation of jaw 8 we prefer to cut a longitudinally elongated ob-

lique or inclined slot 10 in the vertical or upright member of jaw 5 and to cut an oppositely inclined longitudinal slot 11 in the corresponding vertical member of jaw 8. 5 These slots 10 and 11 are so disposed in the center of length of said jaws that portions of said slots will be opposite and register with each other, and at the point of registry or intersection we insert a flattened screw, 10 bolt or similar element 12 transversely through them so that it will extend beyond the vertical plane of the outer surface of the clamping jaws. Bolt 12 is provided with an enlargement or head 13 upon its 15 inner end and a knurled thumb nut 14 or the like is screwed onto its outer extended end for the purpose of locking the parts together. If desired, after the nut 14 has been placed upon the bolt 12 the outer end of the 20 latter may be swayed over to prevent the accidental removal of the nut.

In operation, when it is desired to open the clamping jaws the nut is loosened and bolt 12 is moved toward the position shown 25 in Fig. 3 which will cause the bolt to travel upwardly in slot 10 and downwardly in slot 11 until the ends of the slots are opposite each other in which position the jaws will have been separated to their full extent. 30 The edge of a pad of sales-checks D may then be inserted between the jaws, after which the bolt 12 is adapted to be moved bodily in a reverse direction until the same, acting as a wedge in oppositely inclined 35 slots 10 and 11, will cause the approximation of the respective jaws and will securely clamp the pad, whereupon the nut 14 may be turned down on the bolt to securely lock the parts together. In order to positively 40 guide the movable jaw and prevent longitudinal movement of the same, we prefer to turn back the opposite end edges 15 of the vertical member of stationary jaw 5 to form suitable guideways in which the adjacent 45 end edges of said movable jaw are adapted to travel and thereby retain the latter in parallel relation.

While we have illustrated and described certain specific instrumentalities for carrying out our invention it of course will be obvious to others skilled in the art to which it relates that various changes and modifications may be made without materially departing from the spirit thereof. We wish it 50 understood therefore that such refinements are included within the scope of our invention as expressed in the appended claims.

What we claim as new is:—

1. A clamp for binders comprising a stationary clamping member, a movable clamping member coöperating therewith, one of said members provided with a longitudinal inclined slot, a bolt extended through said slot and adapted to engage both members, 55 and means for securing said bolt in said slot.

2. A clamp for binders comprising a stationary clamping member, a movable clamping member coöperating therewith, one of said members provided with a longitudinal inclined slot, a device extended through said slot and adjustable therein, and means for securing said device in its adjusted position in said slot. 70

3. A clamp for binders comprising a stationary clamping member, a movable clamping member coöperating therewith, one of said members provided with a longitudinal inclined slot, a bolt extended through said slot and adapted to adjustably engage both members, and means for securing said bolt 80 in its adjusted position. 75

4. A clamp for binders comprising a substantially L-shaped clamping jaw, an inverted correspondingly shaped clamping jaw, the vertically disposed members of both 85 jaws slidably engaging each other and one of said vertical members provided with an inclined longitudinal slot, a transverse bolt extended through said slot and adapted to engage both members, and means for securing 90 said bolt in said slot.

5. A clamp for binders comprising a stationary clamping member, a movable clamping member coöperating therewith, each of said members provided with an inclined longitudinal slot, means movable longitudinally in said slots and adapted to open and close said clamping members, and a device 95 for securing said means. 100

6. A clamp for binders comprising a stationary clamping member, a movable clamping member coöperating therewith, each of said members provided with an inclined longitudinal slot, a bolt extended transversely through and movable longitudinally in said 105 slots and adapted to open and close said clamping members, and a device for securing said bolt.

7. A clamp for binders comprising a stationary clamping member, a movable clamping member coöperating therewith, each of said members provided with a longitudinal slot, said slots being oppositely inclined, a bolt extended transversely through and movable longitudinally in said slots and 110 adapted to open and close said clamping members, and a device for securing said bolt. 115

8. A clamp for binders comprising a substantially L-shaped clamping jaw, an inverted correspondingly shaped clamping jaw, the vertical members of said jaws adapted to slidably engage each other and being provided with inclined longitudinal slots, a transverse bolt extended through said slots and adjustable therein to open and close said 120 clamping jaws, and a device for securing said bolt. 125

9. A clamp for binders comprising a substantially L-shaped clamping jaw, an in- 130

verted correspondingly shaped clamping jaw, the vertical members of said jaws adapted to slidably engage each other and being each provided with a longitudinal slot, said slots inclining in opposite directions, a transverse bolt extended through said slots and bodily adjustable therein independent of said clamping jaws to open and close the latter, and a device for securing said bolt in its adjusted positions.

In witness whereof we have hereunto set our hands, at Chicago, in the county of Cook, and State of Illinois, this 26th day of August, 1914.

GEORGE H. BAUGHMAN.
FRANK J. SEMRADEK.
